UNITED STATES PATENT OFFICE

HARRY A. WINTERMUTE, OF PLAINFIELD, AND CARL W. J. HEDBERG, OF MIDDLESEX, NEW JERSEY, ASSIGNORS TO RESEARCH CORPORATION, OF NEW YORK, N. Y., A CORPORATION OF NEW YORK

APPARATUS FOR ELECTRICAL PRECIPITATION

Original application filed November 28, 1927, Serial No. 236,335. Divided and this application filed May 1, 1929. Serial No. 359,683.

This invention relates to the art of electrically precipitating suspended particles from gases, and while applicable to a number of dust cleaning problems, is primarily adapted 5 for the removal of ash and other suspended matter from the gaseous products of combustion from boilers fired with powdered fuel. This problem involves the separation of large 10 quantities of refuse material from great volumes of gas which vary widely in amount due to fluctuations in power loads. As much as possible is collected in a dry state to facilitate handling and removal. Furthermore 15 it is desirable to maintain gas temperatures in order to provide sufficient stack draft and thereby reduce fan operating costs. This type of gas, moreover, may contain a certain percentage of sulfurous gases, so that the use 20 of water in cleaning these gases must be controlled to minimize corrosion of metal parts of the apparatus.

In the use of electrical precipitators for steam plants of the kind described it has been found that there is a certain critical velocity 25 above which effective precipitation falls off very rapidly, due largely to the presence in the combustion gases of grit and unconsumed coal which are not retained at the collecting electrode, as commonly used, but travel along 30 its surface. This content of grit and combustible matter, as well as the volume of the gas, increases at peak loads, and the electrical precipitators must be designed to take care of the maximum or peak load conditions.

In order to take care of these conditions, we subject the gases first to the action of electrical precipitation conditions in the absence of flushing liquid, and then subject the gases from which the more finely divided particles 40 have been removed, to further electrical precipitating conditions, including the use of liquid flushed collecting electrodes to thereby recover whatever suspended matter has escaped collection at the surface of the dry collecting electrodes. We contemplate the use of water as a flushing liquid, although it will be obvious that other flushing liquids may be used.

We are aware that it is not new to flush the 50 surfaces of the collecting electrodes with

water (see Burns Patent No. 1,250,088, December 11, 1917), but under these conditions a sludge of water and precipitated material is formed which is troublesome to handle. We have found that this sludge is caused principally by the mixture of water and the very fine suspended particles of the gas, whereas, in a mixture of water and coarser particles, no sludge is formed, the precipitated matter settling to the bottom of the container. According to our invention the bulk of the fine material is eliminated in a "dry" precipitator and the residual usually coarser material is collected in a "wet" precipitator, so arranged that the difficulties above referred to are minimized.

While various types of flushed collecting electrodes may be used, we have found it preferable to use novel collecting electrodes of the kind hereinafter described, whereby many of the disadvantages of "wet" precipitators are obviated.

Due to the necessary use of pipes for conducting the flushing liquids to the "wet" collecting electrodes, the usual system of suspension of the discharge electrodes is not well adapted to the above-described structure and as part of this invention we have devised a novel supporting system for these electrodes. Although this system is particularly well 75 adapted for use with a "wet" precipitator, it will be understood that it is not limited to use with a "wet" unit, but may be advantageously applied to any form of "dry" or "wet" unit. In this type of suspension, cleaning of 80 the discharge electrodes is facilitated.

The invention will be understood from the accompanying drawings in which:

Fig. 1 is a diagrammatic elevation of an electrical precipitation system having both 90 "dry" and "wet" sections;

Figs. 2 to 6 are illustrations of various forms of collecting electrode units; and

Figs. 2a to 6a show corresponding horizontal cross-sections;

Fig. 7 shows modified forms of electrode units;

Fig. 8 is a section on plane 8-8 of Fig. 7;

Figs. 9 and 10 are elevation and cross-section of a modification;

Fig. 11 is a section through a "wet" precipitator showing general location of collecting electrodes;

Fig. 11a is a partial horizontal section;

Fig. 12 is a sectional elevation on plane A—A of Fig. 11a;

Figs. 13 and 14 show arrangements like Figs. 11 and 12, but having the water-feed at the top.

Referring to Fig. 1, the gases from the furnaces pass through the chamber marked 1, which is divided into a dry section and a wet section, by a partition A. The dry section may be the well-known type of electrical precipitator comprising a series of discharge electrodes 2, mounted in a frame 3, supported on insulators 5, and located between collecting plate electrodes 4.

It will be noted, however, that the suspension for the discharge electrodes 2 is not of the conventional type but involves structural features which are particularly advantageous. The wires 2 are attached to rigid bell-crank members 21, said members being pivoted to the frame 3 at points 22. One end of the last electrode 2 is connected directly to the frame 3, as shown at 23, while one end of the first electrode is connected to a bell-crank supporting a weight 24. By this construction it will be seen that wire electrodes 2 are held taut by the weight 24.

In this section the bulk of the finely divided suspended material is precipitated from the hot gases and drops down into a hopper.

The hot gases then pass into the wet section, which has discharge electrodes mounted on the frame 6 and located between collecting electrodes 7, which may be of any suitable type such as flat or corrugated plates, but are here shown as made up of units 12, to be later described. These collecting electrodes are flushed with water, or other suitable liquid, by means of a pump 8 which delivers the liquid from the bottom of the section to a header 9, to which are connected the hollow units of the collecting electrode, the liquid passing upward through these hollow units, overflowing at the top, and then flowing down over the outside of the units.

The discharge electrodes of this wet section are suspended similarly to those of the dry section, this method of suspension being peculiarly advantageous in a wet section. As seen in Fig. 1, it is necessary for the main feed pipes 9, at the bottom, to be much larger than the vertical pipes 12 which form the collecting electrodes. If the water level is below these main feed pipes, it means that the discharge electrode wires must pass these pipes much closer than the normal gap between the discharge electrodes and the streams of water, which would, of course, result in heavy discharges at these points.

By the construction as shown, the water level

is above the main feed pipe 9, and lever arms 21 project toward the water level but properly spaced therefrom to avoid excessive arcing. An even tension is thus placed on all the discharge wires.

Another advantage particularly useful with a wet section is that corona discharge will take place from the sharp points at the bottom of the lever arms to the surface of the water, thus giving an effective precipitation along the water level. Sneakage of the gas along the surface of the water is thus eliminated and a high gas velocity may be maintained here also.

Another advantage of the lever-arm suspension of discharge wires, whether applied to wet or dry sections, is that the wires are prevented from swaying. When each discharge electrode is weighted it is necessary that each weight be very thin and wide, and these weights sway and twist due to the gas velocity and permit excessive arcing to the collecting electrodes.

When the collecting electrodes 7 are formed by a plurality of units 12, the form and the relative arrangement of the separate units is subject to considerable variation. The units 12 are vertically disposed elements of cylindraceous, i. e. cylindrical or sub-cylindrical, form which may be, and preferably are, so constructed or arranged that the water streams which trap the deposited particles constitute but a minor portion of the total collecting surface. As shown in Figs. 2 and 2a, the units 12 may take the form of hollow pipes which, as shown in Fig. 1, have the wash liquid forced upwardly through the units to overflow at their open upper ends, thus wetting the entire surface of the pipe.

In Fig. 3, the pipe is provided with a cap for better water distribution over the pipe. In Fig. 4, two pipes are arranged side by side with their tops inclined so that the water will flow down the narrow channel or groove between the pipes, as indicated. Fig. 5 shows a special shape of pipe giving the same result as in Fig. 4. Fig. 6 is like Fig. 4 except that the pipes are elliptical in cross-section. These units may be made of any suitable material, such as metal, concrete or earthenware; and they may be arranged either side by side, as shown in Fig. 1, or spaced apart as shown in Fig. 7.

The structure shown in Figs. 7 and 8 includes alternately arranged rod units 12 of substantially circular cross-section, and units 12a of sub-circular section with shallow grooves. This arrangement is advantageous when a relatively large part, but less than the entire collecting electrode surface, is to be wetted to entrap the particles which tend to move along the collecting electrode with the moving gas stream. The arrangement shown in Figs. 9 and 10 includes rod units 12 which have their upper ends cut back, as indicated

at 12b, to permit water from the upper header 11 to flow down the narrow channels between adjacent rods.

With the exception of the form of unit shown in Fig. 2, these collecting electrode systems provide means by which the water is localized in streams which wet but a minor portion of the total collecting electrode surface, whereby the temperature of the gas is not materially lowered, nor is its humidity increased to such an extent that condensed water is deposited in the outlet flues.

The grit, ash, or agglomerated material will be driven by the electrical discharge from the discharge electrodes towards or against the collecting electrode, and will be washed down by the stream of water into the receptacle at the bottom, where it readily settles, thus permitting the water to be recirculated.

Fig. 11 shows in longitudinal elevation the wet section of an electrical precipitator in which the collecting electrodes are formed of units such as are shown in Fig. 4 or 6; and Fig. 12 shows in sectional elevation a similar arrangement showing the form of collecting electrode unit shown in Fig. 2.

Instead of delivering the water from below upwardly through the collecting electrode units, water may be poured from above over the outer surface of the units as shown in Figs. 13 and 14, in which water is delivered from pump 8 to a cross feeder pipe 10, from which extend pipes 11 over each collecting electrode, these pipes 11 having openings in their bottom portions into which project the upper ends of the units 12, these upper ends being of less diameter than the holes in the pipes, so that a stream of water flows down over the outside of the pipe. These ends may be either circular or shaped as shown at 12a (Fig. 8) or 12b (Fig. 10). In this latter instance the units 12 may be located in close proximity, as shown in Fig. 9, and the flow of water is localized in the channel or groove between adjacent units, as is also the case in the forms shown in Figs. 4, 5 and 6. This localization of the stream has the advantage that it is not subjected to the draft of the rapidly flowing stream of gases. The discharge electrodes 2 are preferably arranged opposite these localized streams as shown in Fig. 11a.

In these figures, the discharge electrodes are shown as suspended similarly to those of Fig. 1, except that a weight 24 is used at each end instead of fixing one end electrode directly to the frame.

While we have described special forms of collecting electrodes designed to produce uniformity of water flow, it is obvious that these collecting electrodes may consist of flat or corrugated plates with the water streams supplied at their tops by means of horizontal

feed pipes, as shown in the Burns patent above referred to.

In operation the stream of gases carrying ash, unconsumed coal particles and the like, flows through the dry section which is made of sufficient length to collect and precipitate the bulk of the suspended material in dry condition. The partially cleaned gas still at high temperature and velocity then passes through the wet section which need be only of sufficient length to collect and precipitate the coarser material which has passed the dry section. This material is washed down from the collecting electrodes, but because of its physical character does not form a sludge, but readily settles out from the water in the collecting tank, from which it may be removed by any suitable means.

The gas is not materially cooled in passing through the wet section since only the side portions of the gas stream are brought into contact with the relatively narrow streams of water, particularly when the streams of water are localized in reentrant channels in the collecting electrode surface, nor is there any objectional humidification.

The wet and dry precipitator sections may be connected to a common high tension system or each may be provided with its own source of electrical energy. The system provides additional flexibility as it may be found advantageous to operate such wet sections only at peak load periods when the gas volumes are much above the average.

By the combination described of dry and wet electrical precipitating sections in series or tandem relation, the suspended material in the gases is efficiently precipitated, while the draft conditions are not impaired. The finer particles, which would form a sludge if mixed with water, are recovered in dry condition, and the coarser ash and the like are washed down with water from which they settle without difficulty. This arrangement moreover insures effective precipitation from a gas stream moving at high velocity.

This application is a division of our application Serial No. 236,835, filed Nov. 28, 1927, now Patent No. 1,766,422. Claims to the described method of employing both wet and dry precipitator units are presented in that patent, and the described discharge electrode structures are claimed in a continuation in part application, now Patent No. 1,798,964.

We claim:

1. An electrical precipitator comprising in combination with discharge electrodes, a collecting electrode system comprising a plurality of vertically disposed units of cylindraceous form whose exterior surfaces constitute collecting surfaces opposed to said discharge electrodes, and means for establishing a flow of liquid over the exterior surface of said units.

2. An electrical precipitator as defined in

claim 1 in which the units are curved in cross-section and arranged in proximity thereby forming said vertical channels between adjacent units and discharge electrodes arranged opposite said channels.

3. An electrical precipitator as defined in claim 1 in which the units are formed as pipes having open upper ends and means are provided for forcing the liquid upwardly therethrough.

10 4. An electrical precipitator as defined in claim 1 in which means are provided for recirculating the liquid.

15 5. An electrical precipitator comprising discharge and collecting electrodes, the collecting electrodes being formed with curved surfaces defining vertical channels therein, the discharge electrodes being located opposite said channels, and means for causing streams of liquid to flow down said channels.

20 6. An electrical precipitator comprising discharge electrodes and a collecting electrode formed of hollow units circular in cross-section, arranged in close proximity to form vertical channels between adjacent units, the open upper ends being inclined inwardly, and means for causing liquid to flow upwardly through said units.

25 7. An electrical precipitator comprising vertical collecting electrodes, means for flushing liquid over the surfaces thereof, means for retaining a pool of the flushing liquid beneath said collecting electrodes, the lower ends of said electrodes passing beneath the surface of said liquid, discharge electrodes, and supporting means therefor including levers connected to said discharge electrodes, a portion of said levers projecting toward said pool of flushing liquid.

30 8. The structure as set forth in claim 7 wherein the discharge electrodes and said levers constitute in effect a continuous wire, and means for tensioning said discharge electrodes and levers.

35 45 9. An electrical precipitator comprising a collecting electrode formed of a plurality of spaced vertically extending cylindraceous units whose exterior surfaces constitute collecting electrode surfaces, means for flowing liquid over said exterior surfaces, and discharge electrode means disposed adjacent to said units and opposing said collecting electrode surfaces.

40 50 10. An electrical precipitator comprising a collecting electrode formed of a plurality of spaced vertically extending pipes whose exterior surfaces constitute collecting electrode surfaces, means for flowing liquid over said exterior surfaces, and discharge electrode means disposed outside said pipes and opposing said collecting electrode surfaces.

45 11. An electrical precipitator as set forth in claim 18, said pipes having openings at their upper ends and being provided with means for supplying liquid upwardly through

the interior of said pipes, so as to cause such liquid to flow through said openings and downwardly over the exterior surfaces thereof.

12. An electrical precipitator comprising in combination with discharge electrodes, a collecting electrode system comprising a plurality of spaced vertically disposed units whose exterior surfaces constitute collecting surfaces opposed to said discharge electrodes, and means for establishing a flow of liquid over the exterior surfaces of said units.

13. The invention as set forth in claim 12, wherein said collecting electrode units have reentrant portions providing vertical channels down which the liquid flows in vertical streams.

14. An electrical precipitator comprising the combination with vertically arranged collecting electrodes having opposed vertically undulatory surfaces defining a gas passage, and discharge electrodes in said passage, of means for establishing spaced streams of liquid flowing down the faces of each of said electrodes.

In testimony whereof, we affix our signatures.
